Attorney

UNITED STATES PATENT OFFICE.

LORENZO A. CROWLEY, OF DETROIT, MICHIGAN.

BALLOT PROTECTOR.

1,415,020.

Specification of Letters Patent.

Patented May 9, 1922.

Application filed October 7, 1920. Serial No. 415,442.

To all whom it may concern:

Be it known that I, LORENZO A. CROWLEY, citizen of the United States, residing at Detroit, county of Wayne, State of Michigan, 5 have invented a certain new and useful Improvement in Ballot Protectors, and declare the following to be a full, clear, and exact description of the same, such as will enable others skilled in the art to which it pertains 10 to make and use the same, reference being had to the accompanying drawings, which form a part of this specification.

My invention relates to a ballot marker shown in the accompanying drawings and 15 more particularly described in the following specification and claims.

It is well known that many mistakes are made in the present system of marking ballots with a pencil, due either to carelessness 20 or the inexperience of the voter, in properly indicating upon the ballot, his choice of the candidates running for any particular office.

The object of the present invention is to provide a device adapted to be installed in 25 the voting booth whereby the voter may quickly and readily "mark" his ballot in such manner as will leave no element of doubt in the minds of the officers counting the votes as to each voter's choice of can- 30 didate.

A further object of the invention is to provide means whereby the vote cannot be altered by anyone guilty of maliciously changing the ballot to favor candidates other than 35 those for whom the vote was cast.

A further object of the invention is to provide means for punching and cutting a ballot adjacent to and in line with and through the names of the selected candidates 40 so that the voter's choice of candidates may be indicated without any doubt whatsoever as to his intention.

With the foregoing and other objects in view which will appear as the description 45 proceeds the invention further consists in the combination and arrangement of parts and in the details of construction hereinafter described and claimed, it being understood that changes may be made in the precise embodiment of the invention herein disclosed without departing from the spirit of the same.

In the accompanying drawings forming part of this specification:

Figure 1 is a plan view of the device.

55 Figure 2 is a side elevation of the same.

Figure 3 is a cross-sectional view taken on or about line 3—3 of Figure 2.

Figure 4 is a detail view of one of the punching dies.

Referring now to the letters of reference 60 placed upon the drawings:

A, indicates a base-plate of the main or supporting frame of the device, having ears A' provided with holes for the passage of screws by which it may be secured to a suit- 65 able writing shelf or desk.

B, is a vertically movable plunger sup- 70 ported in a portion of the frame A², over- hanging the base. C, is a knob or handle fitted to the upper end of the plunger and bearing upon a shoulder b formed in the latter. b' is a transverse pin extending through the knob and plunger to secure said knob to the plunger.

D, is a spring encircling the plunger and 75 housed in the counterbored portion of the overhanging frame.—one end of the spring bearing against the end of the knob and the other against the shoulder formed in the supporting frame.

E, is a die-supporting member secured to the end of the plunger by a screw F.

G, is a removable male punching-die sup- 80 ported in the member E by a screw H.

I, I, I, are relatively smaller male punch- 85 ing-dies also supported in the member E by set screws J, J, J, the several dies being aligned with but spaced from the die G.

K, is a rod, secured to the member E by a set screw K', extending up through a hole 90 bored in the overhanging portion of the supporting frame, to guide the vertical movement of the plunger and to prevent horizontal rotation of the die block E.

L, is a U-shaped bifurcated guide secured 95 to the overhanging portion of the casting A and extending downwardly therefrom beneath the plunger and cutting dies—the plunger when actuated being adapted to pass through the open or slotted portion of the 100 guide.

M, is a female die secured to the base of the casting A adapted to co-act with the male cutting dies G, and I, I, I.

Having thus indicated the several parts by 105 reference letters the construction and operation of the device will be readily understood.

Upon entering the booth, the voter having determined upon his selection of candidates for the respective offices, inserts his ballot 110

between the U-shaped guide L, and the die plate M, adjusting the ballot so that the name of the candidates for whom he wishes to vote may be seen through the slot, or bifurcated portion of the guide.— the ballot being so placed that the punching die G, will be in alignment with and immediately preceding the name of the candidate. The plunger is then manually operated thereby causing the several dies to perforate the ballot adjacent to and also directly through the name of the candidate for whom he wishes to cast his ballot. The operation is then repeated for each of the several candidates for whom he wishes to vote. The ballot is then folded in the usual manner and given to the officer in charge of the ballot box, who then deposits the ballot in the latter. If the voter wishes to cast his ballot for a "straight ticket" he inserts the ballot so that the punch will perforate the ballot at the top of the ticket, at a point usually provided to indicate a "straight" party vote. Having thus punched the ballot it will be seen that it cannot be altered by maliciously inclined persons.

Having thus described my invention what I claim is:

1. In a device of the character described, a frame having a portion overhanging its base, a vertical manually operated plunger

sleeved in the overhanging portion, a removable die block secured to one end of the plunger having a plurality of dies thereon and means for removing each of said dies from the said block.

35

2. In a device of the character described, a frame having a portion overhanging its base, a reciprocating plunger, sleeved in the overhanging portion and carrying a removable die block provided with a plurality of removable dies on the end thereof, a set screw for locking the die block to the plunger, and set screws for independently locking each of said removable dies to the die block.

3. In a device of the character described, a frame having a portion overhanging its base, a plunger sleeved in the said overhanging portion, a substantially inverted T-shaped die block carrying a plurality of removable dies, detachably secured to the end of the plunger and a removable guide rod secured to the die block and projecting through the overhanging portion whereby rotation of the die block is prevented.

In testimony whereof, I sign this specification in the presence of two witnesses.

LORENZO A. CROWLEY.

Witnesses:

S. E. THOMAS,

JOHN CONSIDINE, Jr.
